UNITED STATES PATENT OFFICE.

ANDY TOMKO, OF PITTSBURGH, PENNSYLVANIA.

EXTENSIBLE BED.

1,101,361.

Specification of Letters Patent. Patented June 23, 1914.

Application filed April 18, 1914. Serial No. 832,972.

To all whom it may concern:

Be it known that I, ANDY TOMKO, a subject of the King of Hungary, residing at Pittsburgh, in the county of Allegheny and 5 State of Pennsylvania, have invented certain new and useful Improvements in Extensible Beds, of which the following is a specification, reference being had therein to the accompanying drawing.

10 This invention relates to extensible beds and has for its object to provide a bed of such class, in a manner as hereinafter set forth, capable of being conveniently extended when occasion so requires, and foldable in 15 a compact manner when not in use.

Further objects of the invention are to provide an extension bed which is simple in its construction and arrangement, strong, durable, efficient and convenient in its use, 20 readily set up and comparatively inexpensive to manufacture.

With the foregoing and other objects in view, the invention consists of the novel construction, combination and arrangement of 25 parts as hereinafter more fully described and illustrated in the accompanying drawings, wherein is shown an embodiment of the invention, but it is to be understood that changes, variations and modifications can 30 be resorted to which come within the scope of the claim hereunto appended.

In the drawings wherein like reference characters denote corresponding parts throughout the several views:—Figure 1 is 35 a side elevation of the bed when closed; Fig. 2 is a top plan view of the bed when closed; Fig. 3 is an end view, partly in section, with the bed in closed position; Fig. 4 is a detail, broken away, illustrating the position of the 40 mattress support of the shiftable section when the bed is closed; Fig. 5 is a top plan view of the bed when extended; Fig. 6 is an end view of the bed extended; and Fig. 7 is a detail, broken away, illustrating the 45 position of the mattress support when the bed is extended.

An extensible bed in accordance with this invention, includes a stationary and a shiftable section, and the former includes a head 50 piece 8 and a foot piece 9. The head piece 8 is of greater height than the foot piece 9, and with such exception, the head piece 8 is constructed similar to the foot piece 9, and the description of one applies to the other.

55 The foot piece and head piece each consist of a pair of posts 10—11 connected to

gether at their tops by a bridge member 12. The post 10 is connected to the post 11 through the medium of horizontally extending hollow tubular members 12, 13 and 14, 60 and one end of each of said tubular members is attached to a four-way coupling 15 carried by the post 10, and the other end of each of the said tubular members is connected to a T-coupling 16, carried by the post 11. 65 Attached to the posts 10, between the lower pair of the four-way couplings 15 is a sleeve 17, and attached to the posts 11 between the lower pair of the T-couplings 16 is a sleeve 19. 70

Each of the posts 11 of the head and foot pieces is provided with a longitudinally extending socket member 20 formed integral with a sleeve 19, and the said members 20 project toward each other and are adapted 75 to have detachably mounted therein the tongues 21 of the side rail 22 whereby the said socket members 20 are connected together. Each of the posts 10 of the head and foot pieces is provided with a longitudinally extending socket member 23, and the said members 23 project toward each other and are adapted to receive the tongues 24 carried by the other side rail 25 whereby 80 said members 23 are connected together. 85 The side rail 25 has projecting outwardly therefrom a pair of eyes 26.

The shiftable section of the bed includes a foot piece and a head piece, the latter being of greater height than the former, but 90 with this exception, the said foot and head pieces are constructed alike, and the description of one will apply to the other. Each of the foot and head pieces of the shiftable section consists of a post 27 provided with a 95 series of T-couplings 28 which are arranged in alinement with the four-way couplings 15 of the posts 10. Connected with each of the posts 27 is a series of horizontally disposed rails 29 which extend through the 100 four-way couplings 15, and are capable of nesting in the tubular members 12, when the bed is closed. The free ends of the rails 29 are provided with any suitable means to prevent their complete withdrawal from the 105 four-way couplings 15. Each of the posts 27 is furthermore provided between the lower pair of T-couplings 28 with a sleeve 30. Formed integral with the sleeves 30 are oppositely disposed and longitudinally extending socket members 31 which are arranged 110 parallel to the rail 25, and which are adapt-

ed to receive the tongues 32 carried by the mattress support 33 which forms an element of the shiftable section of the bed. The mattress support 33 is also provided with hooks 34 which engage in the eyes 26 when the tongues 32 are seated in the members 31.

The lowermost four-way couplings carried by the posts 10 are provided with oppositely disposed longitudinally extending socket members 35 to receive the tongues 32 of the mattress support 33 when the bed is folded, and as illustrated in Fig. 1. The mattress support 33 is provided with a pair of supporting legs 36. When the bed is folded, the mattress support is connected to the members 35 and is mounted upon its legs 36, as well as being positioned below the rails 22-25 of the stationary section of the bed. When the shiftable section of the bed is extended to the position shown in Fig. 6, the mattress support 33 has the tongues thereof seated in the members 31, and the hooks 34 thereof engage in the eyes 26 whereby the mattress support will be arranged parallel to the rails 22-25 of the stationary section.

What I claim is:—

An extensible bed comprising a stationary

and a shiftable section, said stationary section including head and foot pieces provided with horizontally disposed tubular members and further including rails connecting the head and foot pieces together, said shiftable section including head and foot pieces provided with horizontally disposed rails 30 slidable in said tubular members and further including socket members, and a mattress support detachably engaging with said socket members and with one of the rails of the stationary section for maintaining said support parallel to said rail, said stationary 35 section further provided with socket members for detachably connecting thereto said mattress support when the bed is closed, and said mattress support provided with legs for supporting the inner side thereof when said 40 support is detachably connected to said stationary section.

In testimony whereof I affix my signature in the presence of two witnesses.

ANDY TOMKO.
